UNITED STATES PATENT OFFICE.

ALBERT E. STRIPPEL, OF NEW YORK, N. Y.

STENCIL.

1,221,389.

Specification of Letters Patent. Patented Apr. 3, 1917.

Application filed September 11, 1913. Serial No. 789,305.

To all whom it may concern:

Be it known that I, ALBERT E. STRIPPEL, a citizen of the United States, and resident of the borough of Manhattan, in the city and State of New York, have invented a new and useful Improvement in Stencils, of which the following is a specification.

Heretofore in the manufacture of stencils in which a suitably prepared long fiber fabric has been employed, the fabric has been secured to its oblong frame and stretched across the opening therein with the fibers running transversely of the frame, namely, across the narrow gap therein. As the long fiber fabric, due to its method of manufacture, is much stronger in the direction in which the fibers run than in the direction across the fibers, it has been customary in manufacturing stencils to make the fabric in two or more plies so as to give sufficient strength for withstanding successfully the very hard usage to which the stencils are ordinarily subjected.

I have discovered that by securing the long fiber fabric to the oblong frame with the fibers running longitudinally of the frame, I am enabled to obtain the greatest strength in the direction needed, and by doing this I am enabled to make a very strong and durable stencil with only a single ply of the long fiber fabric, which it has heretofore been impossible to do, thus saving materially in the cost of the stencil and in the expense of manufacturing the same. I also produce a stencil in which the matter impressed thereon by the typewriting machine will not become distorted but will be transferred in the stencil addressing machine very accurately and clearly because of the long fibers running longitudinally of the oblong frame, thereby rendering the stencil more valuable for the purpose intended.

In the accompanying drawing the figure represents in front elevation my improved stencil.

The oblong rectangular frame of cardboard or other suitable material, is denoted by 1. A single ply of long fiber fabric 2, which may be a suitably treated Japanese dental paper is secured to the frame 1 in the usual manner and is stretched across the opening in the frame with the fibers of the fabric running longitudinally of the frame. This will give the stencil the greatest strength across the longest gap in the frame and will also give great strength to the address or other printed matter 3, impressed on the stencil lengthwise of the frame and will keep the relative positions of the several characters of a line much more accurately than heretofore and thereby produce a more legible and better aligned transfer thereof than has been possible where the fibers ran transversely across the matter impressed on the stencil and transversely across the frame.

What I claim is:

1. A stencil comprising an oblong frame and a suitably treated long fiber fabric secured thereto with the fibers running longitudinally of the frame.

2. A stencil comprising an oblong frame and a single ply of suitably treated long fiber fabric secured thereto with the fibers running longitudinally of the frame.

In testimony, that I claim the foregoing as my invention, I have signed my name in presence of two witnesses, this eighth day of September 1913.

ALBERT E. STRIPPEL.
